MACHINE FOR MINING COAL

William S. Galloway, Glasgow, Scotland, assignor
to Mavor & Coulson, Limited, Glasgow, Scot-
land

Application March 11, 1949, Serial No. 81,003
In Great Britain July 10, 1947

7 Claims. (Cl. 262—8)

1

This invention relates to a mining machine of a previously proposed type in use of which cutting of coal or other mineral is effected by a direct shearing or chisel-like action applied by a wedge-like cutter in a horizontal direction behind the face of a mineral seam so as to shear the mineral away in lumps from the seam to a height approximately from floor to roof of the mine.

The present invention comprises a machine for mining coal and other minerals from a mineral seam, by initially stripping an upper-level section of mineral from a length of the face of the seam, performing an intermediate operation (or more than one intermediate operation) consisting of stripping from said length a lower-level section of mineral and also a section at the upper level but at a greater depth from the face of the seam, and finally stripping a lower-level section of mineral left projecting like a ledge throughout said length.

The invention also comprises a mining machine of the type stated which advances along the face of a mineral seam from position to position, the machine having a composite cutter head comprising a group of at least four individual wedge-like cutters that are arranged above-and-below one another and side-by-side and have cylinder-and-ram units respectively for forcing the cutters forwards in a determinate order so as to strip mineral section by section from the face.

The cutter head may include an inclined bottom cutter for stripping mineral from the mine floor and lifting it in the manner of a shovel.

The machine is a vehicle which can be advanced from position to position and in each position performs the initial stripping and the one or more intermediate stripping operations and which thereafter is advanced to another position to deal with the next length of the seam. The final stripping may be performed during each advance of the machine.

A coal-mining machine embodying the invention is shown as an example in the accompanying drawings, in which:

Fig. 1 is a side elevation of the machine and Fig. 2 is a corresponding plan. Fig. 3 is a side elevation, drawn to a larger scale than Figs. 1 and 2, of a central component of the machine which may be regarded as the propulsive vehicular structure of the machine. Fig. 4 is a diagrammatic plan, partly in section, showing one of the wedge-like cutters, the section being approximately on the line IV—IV of Fig. 1.

The machine shown is double-ended; that is

to say, the machine has a composite cutter head at each end so that it can work either to right or left, as viewed say in Figs. 1 and 2. The propulsive vehicular structure according to Fig. 3 carries both cutter heads, which project from said structure in opposite directions.

In the drawings, the floor of the mine is indicated by A, the roof by B and the coal seam by C. The machine is shown in Fig. 2 positioned in a plane prepared for it beyond the left hand end of the seam, the machine being against a face D which is co-planar with the new face about to be formed by the machine behind and parallel to the previously formed face E of the seam C.

The two composite cutter heads of the machine are similar. In the example each of the two cutter heads comprises a group of ten individual cutters arranged as an upper row of five cutters 1, 3, 5, 7 and 9 and a lower row of five cutters 2, 4, 6, 8 and 10, each of them below an upper cutter.

In the example, the propulsive vehicular structure of the machine is a frame 11 equipped with 25 endless tracks 12, or so-called "crawlers," which are fitted with rubber pads 12A to enhance the frictional grip upon the mine floor A. The operation of the tracks 12 is controlled by means of a handle 13. It is from the frame 11 that a framework 14 carrying the two groups of ten cutters extends in opposite directions.

Each cutter is secured to the movable cylinder 15 of one of a group of ten hydraulic units, which are arranged as a compact battery. The ram 16 of each of these units is a stationary fixture 35 on the framework 14 and is provided with inlet and outlet ports 17 and 18. These ports are connected to pipes 19 and 20 for the hydraulic liquid under the control of a distributor valve assembly 21 incorporated in a hydraulic system 40 including as usual a high-pressure pump 22 which is driven by an electric motor 23 supplied through a flexible cable 24 and controlled by a starter 25. It is this motor 23 which is the power unit of the endless tracks 12. These tracks are driven under control of the handle 13 by the motor through gearing which comprises intermeshing bevel gears 26, intermeshing gear-wheels 27 driven thereby, and pin-wheels 28 secured to the shaft 28¹ of the second of these gearwheels. These pin-wheels mesh with sprocket-wheels 30 which are mounted on a shaft 29 and carry the endless tracks 12 at one end of the vehicle frame 11.

The hydraulic system also includes a tank 31 for the hydraulic liquid. The pump 22 as usual

draws the liquid from the tank 31 and, where indicated conventionally at 32 in Fig. 4, discharges the liquid under high pressure through piping 33 to the distributor valve assembly 21. The return piping from the assembly 21 to the tank 31 is indicated by 34.

In the example shown, for simplicity, the valve assembly 21 has six individual valves each operated by one of six handles 21¹ to 26⁶ (see Fig. 3). Each of four of these valves, namely the valves with the handles 21² to 21⁵, controls a pair of the hydraulic units 15, 16 at each end of the machine, namely the units operating the following four pairs of cutters; 2 and 3; 4 and 5; 6 and 7; and 8 and 9. The extreme cutters of each group of ten, namely the cutters 1 and 10, have their hydraulic units 15, 16 controlled individually by the valves with the handles 21¹ and 21⁶. In Fig. 4, the pipes 19 and 20 for two units, one at each end of the machine, and the one handle 21¹ controlling them are shown. It is also shown that the pipes 19, 20 connected to the piston 16 of the cutter 2 have extensions 19A, 20A which are connected to the piston of the simultaneously operating cutter 3 (not shown in Fig. 4). In distinction the pipes 19, 20 for the extreme cutters 1 and 10 have no such extensions seeing that these cutters operate individually.

The cutters 1 to 10 are wedge-like in form (Figs. 2 and 4) and are so arranged that when all of them are fully withdrawn they present an inclined front face which inclines outwards and rearwards to give an overall wedge effect. In Fig. 1, the pair of cutters 4 and 5 are shown advanced, whereas Fig. 2 shows two upper-row cutters 3 and 5 advanced, the others being all fully withdrawn. The assembly of cutters rests upon a bottom cutter 35 whose front face is similarly inclined.

A coal-deflecting ramp 36 secured to the outer side of the machine at each end thereof inclines upwards from the bottom cutter, being located alongside the lowermost level of the coal face.

In the example, the total width of the cutter head measures five feet so that each cutter is designed to cut out a section of coal to a depth of one foot (perpendicular to the plane of the face E). The stroke of each ram is one-and-a-half feet long, so that in each position of the machine it strips from the coal face a length of one-and-a-half feet to a depth of five feet.

In operation, at the starting end (say, the left hand end) of the seam C a place is cut for the machine, and it is manoeuvred into position; say, as shown in Fig. 2. Assume that the right-hand end cutters are fully withdrawn and that they come more or less against the left-hand end of the seam C. The operator turns the handle 21¹ to set only the first cutter 1 in operation, this cutter being in the upper row and at the outer side of the group of ten cutters. This cutter 1 strips out from the seam C an upper section of coal to a depth of one foot from the coal face E. After a full advance of the cutter, the handle 21¹ is turned so that the cutter is quickly withdrawn. Next, the handle 21² is manipulated so that the first lower and second upper cutters 2 and 3 forming a pair simultaneously are advanced and thereafter withdrawn. Next, the handle 21³ is manipulated so that the second lower and third upper cutters 4 and 5 simultaneously are advanced and withdrawn. This procedure is continued. Eventually all but the fifth lower cutter 10 have been oper-

ated; and its valve handle 21⁶ may be manipulated so that the cutter 10 is operated either by itself or simultaneously with the next advance of the machine by operation of the endless tracks 12 under control of the handle 13 to an extent of one-and-a-half feet into its next position. In the advance of the machine, the bottom 35 of the wedge-like head strips and scoops up any bed of coal left on the floor A by the lower cutters 2 to 10, and the entire head forces the broken down coal outwards above the ramp 36. The complete cycle of operations may be designed to occupy about one minute. Thus, it will be manifest that the machine advances stepwise along the coal seam, stripping off coal to a depth of about five feet after each step, the length of which step is about one-and-a-half feet.

Coal above the level of the upper row of cutters can be stripped off from the roof manually without difficulty

When the machine reaches the right-hand end of the coal seam, it is again manoeuvred into a prepared position at that end but five feet further into the coal seam, and thereafter the machine is driven so as to return stepwise in the opposite direction. In this return motion, prior to each step the cutters 1 to 10 at the left hand end of the machine are operated in the order already described under the control of their valve handles 21¹ to 21⁶.

This method of coal-getting is facilitated by use of a conveyor arranged alongside the coal face, between it and a row of roof props; and this conveyor receives from the machine the coal stripped by it as it works along the coal face.

It will be manifest that the machine performs the following method of mining coal length by length from the seam C, namely: initially the cutter 1 strips an upper-level section of mineral from a length of the face of the seam; the pairs of cutters 2 and 3, 4 and 5 and so on, acting in succession, perform an intermediate series of operations each consisting of stripping from said length a lower-level section of coal and simultaneously a section at the upper level but at a greater depth from the original coal face; finally the cutter 10 strips a lower-level section of coal left projecting like a ledge throughout said length.

In the example shown, the machine has a group of five upper and five lower cutters at each end. However, there may be any other practicable number of cutters. There would be two upper and two lower cutters in the simplest construction of the machine. In use of such a machine, there would be only one pair of simultaneously acting upper and lower cutters, and they would perform only one intermediate operation of stripping a lower-level section and simultaneously an upper-level section at greater depth.

In the example, the machine is a vehicle of the "crawler" type. Instead, it may have any other means of propulsion or haulage; and it may include means such as jacks for anchoring it between the floor and roof in each working position.

The machine itself may have means for stripping coal from the roof. For instance, a horizontally extending roof cutter may be connected to or embodied in the top of the wedge-like head.

Although in the example shown the hydraulic units of the cutters are operated in proper order by hand operation of the valve handles 21¹ to 21⁶, the arrangement may be such that the valves

may be operated in the proper order and at the proper times under the control of any conventional timing mechanism driven from the motor 23.

I claim:

1. A mining machine of the type stated for shearing mineral from the face of a seam throughout approximately the full height from floor to roof of the seam, comprising an assembly including four wedge-like cutters, two of them being arranged side-by-side at an upper level and the other two being arranged side-by-side at a lower level, the upper cutters being directly above the lower cutters respectively, cylinder-and-ram units connected to said cutters, each to each, so that when said units are operated they thrust forward the cutters respectively, and control means connected to said units and designed to operate them in the following sequence: initially an outer first cutter at one level is advanced individually to wedge out a section of mineral from the face of the seam, thereafter an outer second cutter at the other level and an inner third cutter at the said one level are advanced simultaneously so that the second wedges off mineral left out-standing by the first and the third wedges out a new section and finally the fourth cutter, namely the inner cutter at said other level, is advanced to wedge off the mineral left out-standing by the third.

2. A mining machine according to claim 1 in which there are a series of four or other even number of wedge-like cutters, half of them at an upper level and the other half of them at a lower level, in which the control means includes two terminal controllers connected to the cylinder-and-ram units of the first and last cutters of the series at different levels for operation of said cutters individually, and in which the cylinder-and-ram units of the remaining cutters at different levels and at different depths in relation to the face of the seam are connected as a pair or pairs to one or more intermediate controllers so that said cutters operate as a pair or in pairs.

3. A mining machine as claimed by claim 2 in which it is the cylinder-and-ram units of the outermost upper cutter and the innermost lower cutter, respectively, that are individually connected to the two terminal controllers for operation of said cutters individually as the first and last members of the series of cutters.

4. A mining machine according to claim 1 in which the cylinder-and-ram units and their wedge-like cutters are so arranged that said cutters when in retracted position combine to form a single large wedge.

5. A mining machine of the type stated for shearing mineral from the face of a seam throughout approximately the full height from floor to roof of the seam, comprising an assembly of an even number, being at least six, of wedge-like cutters, half of them being arranged side-by-side at an upper level and the other half of them being arranged side-by-side at a lower level, each upper cutter being directly above a lower cutter and all of said cutters forming a series starting with one of the two outermost cutters at one of said levels and ending with that one of the innermost cutters which is at the other of said levels, cylinder-and-ram units connected to said cutters, each to each, so that when said units are operated they thrust forward the cutters respectively, and control means connected to said units and comprising two controllers connected to the cylinder-and-ram units of the first and last cutters of the series for operation of said cutters individually, and a plurality of additional controllers each connected to the cylinder-and-ram units of a pair of adjacent cutters at different levels and sidewise offset so that the cutters of the series excepting the first and last will be operated in pairs, the cutters of each pair acting simultaneously.

6. A mining machine as claimed by claim 5 in which it is the cylinder-and-ram units of the outermost upper cutter and the innermost lower cutter, respectively, that are individually connected to the two first-mentioned controllers for operation individually of said cutters as the first and last members of the series.

7. A mining machine according to claim 5 in which the cylinder-and-ram units and their wedge-like cutters are so arranged that said cutters when in retracted position combine to form a single large wedge.
